UNITED STATES PATENT OFFICE

PERCIVAL EDWARD McIVER, OF AUCKLAND, NEW ZEALAND

WAVE RECEIVING APPARATUS

Application filed April 6, 1928, Serial No. 268,067, and in New Zealand May 25, 1927.

This invention relates to systems for eliminating the effects of interfering electric waves upon receiving circuits in radio telephony or telegraphy, and for like purposes in 5 wired telephony or telegraphy.

The object of the present invention is to provide a very efficient means of combating the effects of such interfering electric waves upon the receiving circuits.

10 At present, the methods employed for this purpose may be classed under two general headings:—

(1) The use of a series of tuned amplifier circuits arranged with valves in stages 15 whereby the amplitude of the desired wave is gradually increased at each step, and that of undesired waves are gradually reduced.

(2) The use of special trap or absorption circuits whereby the intensity of the interfering wave is greatly reduced.

Regarding (1), this is certainly a sure way of achieving the object, provided, however, the number of stages is sufficient, particularly when the source of interference is nearby 25 or powerful, but which ultimately becomes unwieldy to operate in the selection of any wave.

In (2) the arrangement is most inefficient, particularly when the interference is powerful, inasmuch as to reduce in any satisfactory degree the intensity of such interference necessitates the absorption of a large amount of power from the circuit, and the absorption reduces seriously the intensity of the desired 35 wave also, which is perhaps already very weak. Even when the arrangement is designed to be of low loss, and this implies sharp tuning, the consequence of such sharp tuning is that no care is taken of side band 40 frequencies inherently attendant upon carrier waves of the modulated type; consequently, the interfering wave breaks through in a very disconcerting manner.

My invention provides means for taking 45 care of the main carrier wave with its attendant side bands and also of possible small variations of main wave frequency of one quarter per cent. (.25%) either way, but does not at any part of the circuit seriously absorb power from the desired wave.

These results are obtained by first collecting (by a transformer or the like means) from the interfering wave in the antenna system a small amount of its energy, the characteristics of which are impressed upon the grid of an amplifying valve or electron discharge relay and, being amplified, the plate circuit of this valve is tuned to and oscillates at this interfering frequency. This amplified energy is then impressed upon a 55 special coupling circuit inserted between the aerial inductance coil and the amplifying receiver proper, in such a direction that the forces of the interfering waves neutralize each other so that no currents of that wave, 60 therefore, flow and influence the amplifier circuits handling the desired wave.

In other words, by taking a small portion of the energy from an electric wave in the aerial of a radio receiver and amplifying the 65 interfering (or undesired) wave only and using this potential to impress its characteristics on another electric circuit in the apparatus in a certain way, the interfering (or undesired) wave in the main circuit is entirely eliminated.

By "tuning", the interfering wave only is carried to the point in the second circuit where the elimination takes place.

The second circuit mentioned (where the 75 elimination takes place), being aperiodic transmits both the desired and the undesired waves; as received by induction from the inductance coil of the antenna acting in one direction. Into this circuit is introduced 80 the opposing potential of the same wave length and intensity as the undesired wave, thus neutralizing the undesired wave.

By referring to the accompanying diagram it will be seen that the aerial inductance A 85 is coupled to one turn C of a coupling or link transformer which is by one turn C₁ coupled to amplifier inductance B, the ends of which lead to the receiver or amplifier J of the desired wave.

Inserted between C and C₁ are another one 90 or two turns C₂ which forms the point at which the interfering waves are eliminated. To bring about this elimination, inductance D is loosely coupled to A and has induced 95 100

therein small electromotive forces from A of the interfering wave which, being amplified and tuned by the system comprising coil E, condenser F and battery G in the plate circuit of the amplifying valve H are impressed on C₂ in a direction such that the electromotive forces produced therein are exactly opposite in phase but of equal magnitude to those produced by the same wave at C. Under such conditions no current of the interfering wave can flow round the circuit C, C₁, C₂, only that of the desired and other weak waves, consequently, no magnetic field of the interfering wave influences B. Having thus eliminated the effects of interferences before the amplifying circuit J is reached it is now unnecessary to use a multiplicity of tuned amplifier or filter circuits as before described in method (1) above.

20 What I claim is:—

1. In a system of the character described, an aerial circuit having an inductance element, a main circuit inductance element, a coupling circuit including terminal coils and 25 an intermediate coil, the terminal coils being inductively related to the aerial and main circuit inductive elements, and means coupling the aerial inductance element and the intermediate coil of said coupling circuit for impressing electromotive forces from an interfering wave on the intermediate coil.

2. A device as claimed in claim 1, characterized in that said means includes an inductance element in inductive relation to the 35 aerial inductance element, a circuit constituted in part by the last mentioned inductance element, and tuning means in said circuit.

3. A device as claimed in claim 1, characterized in that said means includes an inductance element in inductive relation to the aerial inductance element, a circuit constituted in part by the last mentioned inductance element, tuning means in said circuit, 45 and amplifying means in said circuit.

In testimony whereof, I have signed my name to this specification.

PERCIVAL EDWARD McIVER.
